DESIGN FOR A BICYCLE

Samuel A. Snell, Royal Oak, Mich.

Application February 20, 1943, Serial No. 109,588

Term of patent 14 years

To all whom it may concern:

Be it known that I, Samuel A. Snell, a subject of the King of England, residing at Royal Oak, in the county of Oakland and State of Michigan, have invented a new, original, and ornamental Design for Bicycles, of which the following is a specification, reference being had to the accompanying drawing, forming part thereof, in which

Fig. 1 is a side elevational view of a bicycle, showing my new design, and

Fig. 2 is a top plan view thereof, a portion of the handle bar being broken away for convenience in illustration.

The characterizing features of my design reside in the portions shown in full lines in the drawing.

I claim:

The ornamental design for a bicycle, substantially as shown and described.

SAMUEL A. SNELL.
